(57) **CLAIM**

We claim the ornamental design for a video projector, as shown and described.

DESCRIPTION

FIG. 1 is a front, top and right side perspective view of a video projector showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and

FIG. 7 is a right side elevational view thereof;

FIG. 8 is a rear, top and right side perspective view in an operating position thereof;

FIG. 9 is a front elevational view in an operating position thereof;

FIG. 10 is a rear elevational view in an operating position thereof;

FIG. 11 is a top plan view in an operating position thereof; and,

FIG. 12 is a left side elevational view in an operating position thereof.
